UNITED STATES PATENT OFFICE.

CHARLES SEYMOUR, OF DEFIANCE, OHIO, ASSIGNOR TO THE DEFIANCE MACHINE WORKS, OF SAME PLACE.

SPOKE-DRIVER.

SPECIFICATION forming part of Letters Patent No. 426,147, dated April 22, 1890.

Application filed January 8, 1890. Serial No. 336,259. (No model.)

To all whom it may concern:

Be it known that I, CHARLES SEYMOUR, of Defiance, in the county of Defiance and State of Ohio, have invented certain new and useful Improvements in Spoke-Drivers; and I do hereby declare the following to be a full, clear, and exact description of the invention, such as will enable others skilled in the art to which it appertains to make and use the same.

10 My invention relates to an improvement in spoke-drivers; and the object is to provide simple and expeditious mechanism for driving spokes into their hubs, and, further, to provide means for controlling the motion of the machine and for changing the adjustment of the various parts to suit the length of the spokes, or, in other words, the size of the wheel; and my invention consists in a mallet and means for operating the mallet, in combination with seats for holding the hubs while the spokes are being driven in, and mechanism for changing the positions of the various parts.

15 In the accompanying drawings, Figure 1 is a side elevation. Fig. 2 is an end elevation. Fig. 3 is a modification, and Fig. 4 is a detailed view.

20 A represents the standard of the machine, and 1 is the base, to which the standard is bolted or otherwise secured. A shaft 2 lies across the top of the standard, where it is revolvably supported in suitable journal-boxes. On one end of this shaft a clutch is located. This consists of the male section 3, which is rigidly secured on the outer end of the shaft, and the female section 4, loosely mounted on the shaft and comprising the belt-wheel portion 5, over which the belt which drives the machine passes, and the 25 flange 6, which receives the flange of section 3. The loose section 4 is slid back and forth by the shipper 7, and the latter is loosely connected with the hub 8 of the section 4. This connection is effected by means of a pair of pins 9 9, which project in opposite directions from the band on the hub into the elongated slots 10 10 in the forked end of the shipper. This shipper is fulcrumed at point 12, and from here an arm 13 projects approximately 30 at right angles. Connected with the outer end of this arm is a pitman 14, which con-

ncts at its opposite end with the arm 15 on rocking treadle 16. By placing the foot upon this treadle the sliding section is forced into contact with the fixed section, and in this manner the motion of the former is communicated to the latter, and thus the shaft is rotated.

35 The mallet 17, which drives the spokes, is connected with the opposite end of the shaft, and the handle may be rigidly secured to the shaft, as shown in Fig. 1, if preferred, or it may have sliding connection therewith, as shown in Fig. 3, according to the character of the work done, whether light or heavy. In 40 the construction shown in Fig. 1 a spring 18 is connected at one end to this mallet, and the opposite end is connected by a stem 19 to the support A at any one of the points 20 20. In the other construction—namely, that 45 shown in Fig. 3—the handle of the mallet slides in a plate 21, secured to the end of the shaft.

50 The tendency of the spring 18 is to throw the handle in the direction the arrow points, the function of the spring being to return the hammer to its normal position; but this tendency is counteracted by the eccentric semi-circular guideway 22, which is adjustably secured to the support by bolts 23 or equivalent devices. An anti-friction roller 24 on this handle, or on the block to which it is secured, is adapted to travel on the guideway during the downward stroke. The guideway is so arranged that it throws the mallet out 55 in position to strike the spoke on the end. By this time the roller passes from the guideway and the spring slides the mallet back, so that it can make a complete revolution. When the roller reaches the guideway again, 60 it traverses it as before. The spoke being driven is held by the binding-clamp 25, which has an anti-friction roller on its free end to rest against the spoke. This clamp is operated by the hand-lever 26. The pad 27 lies 65 against the opposite edge of the spoke. The binder-stock 28 is adjustable on the support to accommodate the various lengths of hubs, so that the clamp may be moved forward or 70 backward to the required position.

75 The hub is held in the seats 29 29, where they are retained in position by adjustable

blocks 30-30. These seats are rendered adjustable by the screws 31-31-31, which are connected with the seat. One of these screws is connected directly with one of the seats from beneath, another with the other seat from the side by passing through a box 32, and this box is slid up or down by the third screw, which passes through this box.

Changes in the various details of construction are obviously possible, and hence, they being contemplated, need not be specifically described, and therefore I do not wish to limit myself to the precise construction herein set forth; but,

Having fully described my invention, what I claim as new, and desire to secure by Letters Patent, is—

1. The combination, with a support and shaft thereon, of a mallet connected with the shaft and a spring connected with the mallet, substantially as set forth.

2. The combination, with a support and shaft thereon, of a mallet connected with the shaft, a spring connected with the mallet, and clutch mechanism on the shaft, substantially as set forth.

3. The combination, with a support and shaft thereon, of a mallet appended to the shaft, and a guideway and spring for changing the position of the mallet, substantially as set forth.

4. The combination, with a support, a shaft thereon, and a mallet having sliding connection with one end of the shaft, of clutch mechanism for starting and stopping the shaft, and means for operating the clutch mechanism, substantially as set forth.

5. The combination, with a support, a shaft thereon, and a mallet having sliding connection with the shaft, of a guideway secured to the support eccentric to the shaft, and an

anti-friction roller adapted to traverse the guideway, substantially as set forth.

6. The combination, with a support, a shaft thereon, a guide-plate on one end of the shaft, 45 a mallet adapted to slide in the guide-plate, and a spring connecting the mallet with the plate, of a semicircular guideway adjustably secured to the support, and an anti-friction roller which traverses the guideway during a portion of the revolution of the mallet and during its contact therewith counteracts the effect of the spring, substantially as set forth.

7. The combination, with a support, a shaft, a guideway, and a mallet having sliding connection with the shaft, of a clutch on the shaft consisting of a fixed and movable section, and means for shifting the latter to throw the sections in or out of contact with each other, substantially as set forth.

8. The combination, with a support, a shaft, and mallet having sliding connection with the shaft, of adjustable hub-seats, an adjustable binding-stock, and a pivoted binding-clamp, substantially as set forth.

9. The combination, with a support, a rotary shaft, and mallet, of adjustable hub-seats, screws connected with the seats and adapted to shift them when turned, an adjustable binding-stock, a binding-clamp pivoted to the latter, the latter having an anti-friction roller which bears on the spoke, and a fixed pad, against which the spoke rests, substantially as set forth.

In testimony whereof I have signed this 75 specification in the presence of two subscribing witnesses.

CHARLES SEYMOUR.
